CLAIM

The ornamental design for a container with lid, as shown and described.

DESCRIPTION

FIG. 1 is an isometric view of a container with lid showing my new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another isometric view thereof shown in an open configuration for clarity of disclosure.

The broken lines in the drawings illustrate portions of the container with lid that form no part of the claimed design.
